UNITED STATES PATENT OFFICE.

THOMAS E. WASHBURN AND ZACHARIAH TAYLOR HULL, OF COALINGA, CALIFORNIA.

SPOOL HOLDER.

Application filed June 17, 1922. Serial No. 568,925.

To all whom it may concern:

Be it known that we, THOMAS E. WASHBURN and ZACHARIAH TAYLOR HULL, citizens of the United States, and residents of Coalinga, in the county of Fresno and State of California, have invented certain new and useful Improvements in Spool Holders, of which the following is a specification.

This invention relates to a spool holder.

10 The invention more particularly relates to a holder for a spool of thread or the like. A spool of thread from which pieces or lengths are taken for hand sewing is usually retained in a basket or laid upon a table or 15 stand and often becomes lost or the thread becomes unwound from the spool and causes inconvenience. With this in mind it is the object of the present invention to provide a holder for a spool of thread which will 20 serve for supporting a spool of thread to be easily unwound and thus obviate the inconvenience of the loss of the spool of thread or unwinding of the thread therefrom as above referred to.

25 It is also an object of the invention that the spool holder be adapted for retaining a package of needles and thus to increase the convenience of the article.

30 It is a further object of the invention that the spool holder be provided with a thread cutter and thus again to increase the advantages thereof.

35 It is also an important object of the invention that the spool holder be of such design and construction that the same may be formed from one piece of sheet metal or the like.

40 Other objects and objects relating to details of construction will be hereinafter described.

The invention is illustrated by way of example in the accompanying drawings, in which,

45 Figure 1 is a perspective view of a spool holder constructed in accordance with the present invention.

Figure 2 is a rear end elevation of the same.

50 Figure 3 is a view in side elevation of the same.

Figure 4 is a bottom plan view of the blank from which the spool holder may be stamped or formed.

55 Referring to the drawings more particularly in Figure 4 the blank shown consists in a base or body portion 10 which is rec-

tangular in shape and having formed at each end an extension 11 which terminates in a circular portion 12. Each extension 11 has its circular portion formed with an indentation or depression to provide upon its opposite surface a protrusion 13 which is hemispherical in shape as illustrated in Figure 3; these extensions are bent upwardly then inwardly and again upwardly so that the spool supporting arms resulting from such bendings may yield horizontally and vertically.

60 The extension 11 at one end of the blank has its circular portion 12 formed with a projection 14 in which there is provided a V-shaped notch to form the two cutting edges 15, said edges terminating at their lower ends in a circular opening 16. At the other end of the body portion of the blank 70 there is formed a pair of lug extensions 17, one occurring upon each side of the associated extension 11.

65 In forming the spool holder from the blank described, the longitudinal edges of the body portion of the blank are bent downwardly and then inwardly upon the dotted lines 18 and 19, respectively. The portions 21 are thus provided which serve as 75 supporting means for the remainder of the body portion 10 and thus to provide a base generally indicated by the reference character B for the spool holder. The longitudinal edge portion formed by bending the body portion of the blank upon the line 19 80 in each instance extends upwardly and then inwardly to provide the two ledges 22 which are in spaced relation with the bottom of the base B and adapted to support a package of needles. The lugs 17 are bent downwardly as shown in Figure 2 and thus to 85 prevent the package of needles from sliding from the rear end of the needle holder. The extensions 11 are bent upwardly to 90 form the two uprights R and preferably so 95 bent that the curved portion 23 occurs in each upright adjacent the base B in order to give the same the required resiliency vertically and horizontally.

100 As shown in Figure 1 a spool of thread S may be positioned between the uprights R. The protrusions 13 extend into the bore of the spool of thread and thus support the spool for rotative movement whereby the thread thereon may be unwound. The spool 110 of thread may be easily removed after the thread thereon has been used. The upright

R having the protrusion 14 affords a thread cutter and this should occur at the forward end of the holder. Also the package of needles is inserted in the forward end of the holder.

What we claim is:

1. A spool holder made from a one-piece blank for the purpose described, comprising a rectangular body portion having a reduced extension at each end and each extension terminating in an enlarged circular portion, said circular portions each provided with a depression providing a protrusion upon opposite faces of the extensions, said extensions being bent upwardly, then inwardly and again upwardly on transverse lines, providing spool support-

ing standards which may yield horizontally and vertically.

2. A spool holder of the character described, comprising an elongated sheet metal base or body portion with its longitudinal edges folded downwardly and inwardly and upwardly providing longitudinal supports for the device and also a pair of opposing ledges whereby to support a package of needles, and downwardly extending tangs at the rear end of the body portion adapted to cooperate with said ledges to hold the needle package in proper position and to prevent said package sliding through the rear end of the device.

THOMAS E. WASHBURN.
